UNITED STATES PATENT OFFICE.

PHILIP MARQUA, OF ST. LOUIS, MISSOURI.

SHOE-SHINE STAND.

Application filed July 12, 1922. Serial No. 574,434.

To all whom it may concern:

Be it known that I, PHILIP MARQUA, a citizen of the United States, residing at St. Louis, State of Missouri, have invented 5 certain new and useful Improvements in Shoe-Shine Stands, of which the following is a specification.

My invention has relation to improvements in shoe-shine stands, and consists in 10 the novel features of construction more fully set forth in the specification and pointed out in the claims.

The object of the present invention is to combine in a single stand a foot-rest and a 15 box for the shoe-shining supplies, the former being housed in the latter when not in use, but coming into operative position when the box is opened. A further object is to provide a device of this character that is simple, 20 but substantial, and that may be constructed at low cost. Further advantages will be better apparent from a detailed description of the invention in connection with the accompanying drawings, in which—

25 Fig. 1 is an end elevation of the stand with the foot-rest housed inside of the closed box; Fig. 2 is a cross-section of the stand with the box open, taken on the line 2—2 of Fig. 3; Fig. 3 is a plan view of the stand 30 with the box open; Fig. 4 is a vertical zig-zag section taken on the line 4—4 of Fig. 3; and Fig. 5 is an enlarged sectional detail showing the hinged connection of one box section with the foot-rest support.

35 Referring to the drawings, 1, 1, represents the side walls of the stand, each of which is provided with legs 1', 1', and beveled edges 2, 2, connecting the top and side edges. The sides 1, 1 are connected by a 40 bridge member 3 fitted into a vertically disposed groove α at the center of said sides 1, 1, and by bottom members 4, 4 secured in transverse grooves β , β in the sides some distance below the bridge member 3, said 45 members 4, 4 being spaced apart at the center of the sides 1, 1 by the width of grooves α , α .

The bridge member 3 is provided with vertically disposed openings δ , δ spaced 50 apart and spaced from the sides 1, 1, and rods 5, 5 are adapted to traverse these openings, said rods having a foot-rest 6 secured to their upper ends and a bar 7 secured to their lower ends between nuts n , n' , the ends 55 of the bar 7 being fitted into grooves a , a in the end walls 1, 1 wherein they are adapt-

ed to slide. Box sections A, A' are positioned between the end walls 1, 1, and the inner walls 8, 8' of said box sections have hinge pins 9, 9' secured to their upper edges. 60 A hinge plate 10 having eyes 11, 11' is passed over each rod 5 and is clamped to bar 7 by each of the nuts n , n' , the pin 9 of box section A traversing eyes 11 of the hinge plates, and the pin 9' of box section 65 A' traversing eyes 11' of said plate thereby securing said sections to the bar 7 in hinged relation. To permit the eyes 11, 11' of the hinge plate 10 to envelope the hinge pin 9, 9', the walls 8, 8' are each provided. 70 with a notch 12 in their upper edges opposite said hinge plate.

By virtue of the hinged connection between the box sections A, A' and bar 7 and the sliding movement of said bar, it 75 will be apparent (Fig. 2) that if the sections are swung upwardly from an open position to a closed position (Fig. 1) the hinge plate 10 will move downwardly, bar 7 sliding freely in grooves a , a and the 80 lower edges e , e of the sections moving outwardly along the bottom members 4, 4 until the sections A, A' are in a vertical position, at which time the ends 13, 13 of the sections will come together to form the top 85 of the closed stand.

The side walls 1, 1 are beveled off at the corners to permit the edges 13, 13 to clear the side walls readily when the box sections are being thrown open for use. Triangular blocks 14, 14 are secured to sides of the sections A, A' adjacent the ends 13, 13 for the purpose of filling out the corners of the walls 1, 1 when the sections A, A' are closed (Fig. 1). 90

When the sections A, A' are opened out, the bar 7 will be raised in the grooves a , a , moving the rods 5, 5 upwardly and bringing the foot-rest 6 in position for use. 95

Having described my invention, I claim: 100

1. A shoe-shining stand comprising a pair of side members, a bridge member connecting said side members, a foot-rest projecting upwardly from said bridge member, a bar slidably mounted between said side members and connected to said foot-rest, and a pair of box sections hinged to said bar. 105

2. A shoe-shining stand comprising a pair of side members a bridge member connecting said side members, a foot-rest projecting upwardly from the bridge member and slidably mounted therein, and a pair of box 110

sections cooperatively connected in hinged relation with the foot-rest.

3. A shoe-shining stand comprising a pair of side members, a bridge member connecting said side members, a pair of rods slidably mounted in the bridge member, a foot-rest secured to the rods at one end and a bar secured to the rods at the opposite end, a pair of box sections hinged to the bar and adapted to be closed over the foot-rest when the stand is not in use.

4. A shoe-shining stand comprising a pair of side members, a bridge member connecting said side members, a bar slidably mounted between said side members, a foot-rest projecting upwardly from the bridge member and secured to said bar, and a pair of box sections hinged to said bridge. 15

In testimony whereof I hereunto affix my signature.

PHILIP MARQUA.
